[57] **ABSTRACT**

The present invention is related to certain new basic α -nortricyclyl-(3)-benzyl ethers and salts, quaternary ammonium salts and N-oxides thereof, pharmaceutical composition comprising the same as active principle and a process for the treatment of spasm.

3 Claims, No Drawings

BASIC α -NORTRICYCLYL-(3)-BENZYL ETHER,
AND THE SALTS THEREOF

It has been found that compounds having the general formula I

wherein R₁ is hydrogen, a halogen atom, a lower alkyl group having from one to four carbon atoms, the trifluoromethyl or a lower alkoxy group having from one to four carbon atoms, R₂ is hydrogen, a straight or branched chain alkyl group having from one to four carbon atoms or the ethinyl group, —alk— is —CH₂—, —CH₂CH₂— or

and A is the groupment having the formula

wherein R₃ and R₄ represent lower alkyl groups having from one to four carbon atoms or, together with the nitrogen atom to which they are bound, represent the piperidino, morpholino or the pyrrolidino group and R₆ is hydrogen or the methyl or ethyl group, or A

wherein R₅ is a lower alkyl group having from one to four carbon atoms, and the acid addition salts, quaternary ammonium salts and N-oxides thereof, have valuable properties, in particular as therapeutically active compounds.

Acid addition salts of the compounds of formula I are in particular those of pharmacologically acceptable acids.

Quaternary salts of the compounds of formula I are in particular those deriving from alkyl halides, in particular chlorides and bromides, and alkyl sulfates having one or two carbon atoms in the alkyl group.

Because of their particular good properties such compounds of formula I are preferred wherein R₁ is hydrogen, fluorine, chlorine or bromine or the methyl,

methoxy or trifluoromethyl group, R₂ is hydrogen, the methyl or ethinyl group, —alk— is the methylene or the ethylene group, and R₃, R₄ and R₅, which may be identical or different from each other, represent methyl or ethyl groups.

Preferred acid addition salts are those deriving from hydrochloric, sulphuric, phosphoric, acetic, glycolic, lactic, malic, succinic, tartaric, citric, benzoic, β -hydroxy-napthoic and embonic acid. Particularly preferred are the hydrochlorides.

The compounds of the general formula I and the acid addition and quaternary salts and N-oxides thereof are effective as spasmolytics and, as long as they represent tertiary amines, antiallergics, antidepressives and tremor inhibitors.

The compounds have been tested locally on the small intestine of guinea-pigs according to N. BROCK, D. LORENZ and H. BARTLING, Arch. exp. Path. Pharmacol. 215, (1952), pgs. 512 to 524. The tested compounds have been applied intravenously. The effective dose DE 75 has been determined as that dose which reduces for 75 percent spasms caused by administration of Neostigmine or barium chloride.

The results are as follows:

a. Tertiary amines (Table 1):

In comparison to the known similar endocyclic product E, the compounds A and B according to the present invention are myotrop-spasmolytically three to four times more effective (BaCl₂ spasm). The neurotrop-spasmolytical effectiveness of B corresponds to that of the known compound E while compound A is four times more effective (Neostigmine spasm). The further known comparative test compounds Avacan and Papaverine have been less effective than compounds A, B and E.

b. Quaternary ammonium salts (Table 2):

The tested quaternary ammonium compounds are characterized by a particularly high spasmolytic activity.

With respect to the neurotrop-spasmolytical effectiveness compound F according to the present invention has been more effective for 32 percent and compound G according to the present invention has been effective 93 percent more effective than the known comparative test compound ciclonium bromide.

With respect to the spasm caused by barium chloride, compound G has been twice as effective and compound F has been 25 percent more effective than ciclonium bromide. Compound G according to the present invention has been more effective than the further known comparative test compound methanteline bromide both with respect to the musculotrop- and the neurotrop-spasmolytic effectiveness. The neurotrop-spasmolytic effectiveness of compound F according to the present invention also has been significantly higher than that of the known compound methanteline bromide.

TABLE 1.—SPASMOLYTIC EFFECTIVENESS OF TERTIARY AMINES

Test compound	Spasms caused by Neostigmine				Spasms caused by BaCl ₂			
	DE 75		Relative effectiveness calculated to the test compound E=1.00		DE 75		Relative effectiveness calculated to the test compound E=1.00

The product names given in the first column of Tables 1 and 2 have the following significance:

Symbol	Significance
A	Compound 5212: β -diethylamino-ethyl-[α -nortricycl-(3)-benzyl] ether hydrochloride; product according to Example 1
B	Compound 5237: β -diethylamino-ethyl-[α -methyl- α -nortricycl-(3)-benzyl]-ether hydrochloride; product according to Example 5
C	Pauperin
D	Avacan ¹⁰ : α -(β -diethylamino-ethyl)-phenylacetic acid isoamyl ester hydrochloride; Example 1 of German Patent Nr. 842,204
E	Compound 024.002: β -diethylamino-ethyl-(2,5-endomethylene- Δ^3 -tetrahydro- α -methyl-benzhydryl)ether hydrochloride; Example 7 of German Patent Nr. 1 052 982
F	Compound 5213: β -diethylamino-ethyl [α -nortricycl-(3)-benzyl] ether bromomethylate, product according to Example 10
G	Compound 5238: β -diethylamino-ethyl [α -methyl- α -nortricycl-(3)-benzyl] ether bromomethylate, product according to Example 5
H	Methanteline bromide: xanthene-9-carboxylic acid-3-diethylamino-ethyl ester bromomethylate
J	Cletonium bromide: β -diethylaminoethyl-(2,5-endomethylene- Δ^3 -tetrahydro- α -methyl-benzhydryl) ether bromomethylate

The compounds according to the general formula I and the acid addition salts and quaternary ammonium salts and N-oxides thereof are produced by reacting a compound of the general formula II

with a compound of the general formula III

in the presence of an acid binding agent at an elevated temperature, in the above general formulas II and III R₁, R₂ and —alk— having the same meaning as in formula I, X representing a halogen atom, where Y represents a hydroxy group, or X representing the hydroxy group, where Y is a halogen atom, and A₁ has the same meaning as A in formula I or is the groupment —CH₂Hal, Hal being a halogen atom, and, if A₁ is the groupment —CH₂Hal, reacting the resulting compound with a secondary amine of the general formula IV

15 wherein R₃ and R₄ have the same meaning as in the general formula I,

in the presence of an acid binding agent at an elevated temperature and, if desired, converting the thus obtained compounds of formula I in an acid addition salts 20 or an N-oxide or, by reaction with an alkyl halide or an alkyl sulfate, into a quaternary ammonium compound.

The process which gives the best results and therefore is preferred, starts with such compounds of the general formula II, wherein X is the hydroxy group, and 25 a compound of the general formula III, wherein Y is a halogen atom, preferably a chlorine or bromine atom.

The conversion of the compounds of formula I into the corresponding N-oxides is effected by subjecting the compounds of formula I to reaction with hydrogen-peroxide or with a peroxy acid such as peroxy acetic or 30 benzoic acid.

The preferred acid binding agents are metallic sodium, sodium hydride, sodium amide, sodium oxide, sodium or potassium hydroxyde or sodium or potassium 35 um alcoholates.

Preferably, the reaction is carried out in a suitable inert organic solvent such as benzene, toluene or xylene.

40 Preferably, the reactions are carried out at an elevated temperature between about 50° C and the boiling point of the reaction mixture at atmospheric pressure.

The following examples serve to further illustrate the 45 present invention.

EXAMPLE 1

β -Diethylamino ethyl [α -nortricycl-(3)-benzyl] ether 50 200 g. of α -nortricycl-(3)-benzyl alcohol are added with stirring to a suspension of 49 g. of sodium amide in 1,200 ml. of toluene. After standing for 10 minutes, the reaction mixture is heated to boiling and 170 g. of β -diethylaminoethyl chloride are added thereto slowly. The reaction mixture then is refluxed with stirring for 2 hours.

55 After cooling, the reaction mixture is washed with water, the toluene is distilled off and the residue is subjected to fractional distillation in a vaccum.

Bp._{0.01 mm}: 119°–121° C.

60 Yield: 248 g.=84 percent of the theoretical.

For preparing the corresponding hydrochloride, the above obtained base is dissolved in anhydrous ether and a little less than the theoretical amount of hydrogen chloride dissolved in anhydrous ether is added thereto with stirring. The precipitated hydrochloride is filtered off with suction and recrystallized from ethyl acetate.

Fp.: 107°–110° C.

EXAMPLE 2

 β -Dimethylaminoethyl[α -nortricyclyl-(3)-benzyl] ether

100 g. of [α -nortricyclyl-(3)-benzyl] alcohol are added to a suspension of 15 g. of sodium hydride in 700 ml. of toluene and are reacted with 67 g. of β -dimethylaminoethyl chloride as described in Example 1.

B.p._{0.02 mm.}: 110°–115° C.

Yield: 93 g. = 68.5 percent of the theoretical.

Hydrochloride

Fp.: 138°–141° C. (recrystallized from ethyl acetate).

N-Oxide hydrochloride: Fp.: 147°–153° C.

EXAMPLE 3

 β -Dimethylaminoethyl [α -nortricyclyl-(3)-benzyl] ether bromomethylate

31 g. of β -dimethylaminoethyl[α -nortricyclyl-(3)-benzyl] ether (prepared according to Example 2) are dissolved in 250 ml. of acetone. 22 g. of methyl bromide are added thereto. The mixture is heated to boiling for 1 hour and, after cooling, 1,500 ml. of anhydrous ether are added thereto. The precipitated quaternary ammonium salt is dissolved another time in as little an amount of acetone as possible and again precipitated by the addition of ether

Fp.: 168°–170° C.

Yield: 35 g. = 83 percent of the theoretical.

EXAMPLE 4

 β -Dimethylaminoethyl [α -nortricyclyl-(3)-benzyl] ether

100 g. of α -nortricyclyl-(3)-benzyl alcohol and 67 g. of β -dimethylaminoethyl chloride are reacted in 700 ml. of toluene as described in Example 1. 11.5 g. of metallic sodium suspended therein is used as condensing agent.

B.p._{0.04 mm.}: 108°–112° C.

Yield: 9p g. = 66.3 percent of the theoretical.

Chloromethylate

The product is produced analogous to Example 3.

Fp.: 184°–187° C. (recrystallized from a mixture of alcohol and ether).

Iodomethylate

The product is produced analogous to Example 3.

Fp.: 93°–97° C. (recrystallized from a mixture of acetone and ether).

Methyl sulfate

The product is produced analogous to Example 3.

Fp.: 172°–174° C. (recrystallized from acetone).

EXAMPLE 5

 β -Diethylamino-ethyl- [α -methyl- α -nortricyclyl-(3)-benzyl]-ether

73 g. of α -methyl- α -nortricyclyl-(3)-benzyl alcohol are added with stirring to a suspension of 16.5 g. of sodium amide in 100 cc. of benzene. The resulting mixture is heated to boiling. A benzolic solution of β -diethylamino-ethyl bromide (produced by adding a sufficient amount of soda lye to 112 g. of β -diethylaminoethyl bromide hydrobromide, extracting the base with 500 cc. of benzene and drying the benzolic solution over anhydrous sodium sulfate) is added to the above suspension slowly dropwise. The mixture

then is heated to boiling for two hours and worked up as described in Example 1.

B.p._{0.005 mm.}: 130°–136° C.

Yield: 86 g. = 81.1 percent of the theoretical.

5 Hydrochloride

Fp.: 121°–123° C. (recrystallized from ethyl acetate).

Bromomethylate

Fp.: 167°–168° C. (recrystallized from a mixture of acetone and alcohol).

10

EXAMPLE 6

 β -Piperidinoethyl [α -nortricyclyl-(3)-benzyl] ether

47.5 g. of α -nortricyclyl-(3)-benzyl alcohol are added

15 to a suspension of 27 g. of powdered potassium hydroxyde in 300 cc. of toluene. The resulting reaction mixture is heated to boiling. 44 g. of α -piperidinoethyl chloride are added thereto dropwise while boiling the reaction mixture. After termination of the addition the reaction mixture is heated to boiling for another two hours. After cooling, the reaction mixture is washed with water, worked up as previously described and finally subjected to fractional distillation.

20 Yield: 34 g. = 46 percent of the theoretical.

B.p._{0.01 mm.}: 151°–**° C.

Hydrochloride

Fp.: 173°–185° C. (recrystallized from ethyl acetate).

Bromomethylate

Fp.: 164°–185° C. (recrystallized from a mixture of alcohol and ether).

25

Analogous to the previous Examples, the following further products according to the present invention have been prepared.

Ex- ample	Chemical nomenclature	Properties
7.....	β -Dimethylaminoethyl[α -nortricyclyl-(3)-benzyl] ether.	Base: B.P. _{0.02 mm.} : 110–115° C.; Ethosulfate: F.P.: 115–117° C.
8.....	γ -Diethylaminopropyl [α -nortricyclyl-(3)-benzyl] ether.	Base: B.P. _{0.05 mm.} : 116–120° C.; Hydrochloride: F.P.: 131–133° C.; Bromomethylate: F.P.: 142–144° C.; Iodo- methylate: F.P.: 162–165° C.
9.....	β -Diethylaminoisopropyl [α -nortricyclyl-(3)-benzyl] ether.	Base: B.P. _{0.05 mm.} : 117–120° C.; Hydrochloride: F.P.: 136–144° C.; Bromomethylate: F.P.: 201–203° C.
10.....	β -Diethylaminoethyl [α -nortricyclyl-(3)-benzyl] ether.	Base: B.P. _{0.01 mm.} : 119–121° C.; Bromomethylate: F.P.: 149–151° C.; Citrate: F.P.: 90–94° C.
11.....	β -Diethylaminoethyl [α -nortricyclyl-(3)-p-methyl benzyl] ether.	Base: B.P. _{0.01 mm.} : 130–135° C.; Hydrochloride: F.P.: 130–132° C.; Bromomethylate: F.P.: 155–157° C.
12.....	β -Dimethylaminoethyl [α -methyl- α -nortricyclyl-(3)-p-chloro benzyl] ether.	Base: B.P. _{0.1 mm.} : 134–137° C.; Hydrochloride: F.P.: 148–151° C.
13.....	β -Diethylaminoethyl [α -nortricyclyl-(3)-p-methoxybenzyl] ether.	Base: B.P. _{0.05 mm.} : 136–142° C.; Hydrochloride: F.P.: 101–103° C.; Bromomethylate: F.P.: 166–168° C.
14.....	β -Diethylaminoethyl [α -nortricyclyl-(3)-o-chloro benzyl] ether.	Base: B.P. _{0.1 mm.} : 128–132° C.; Hydrochloride: F.P.: 98–100° C.; Bromomethylate: F.P.: 128–142° C.
15.....	β -Diethylaminoethyl [α -nortricyclyl-(3)-p-chlorobenzyl] ether.	Base: B.P. _{0.01 mm.} : 128–132° C.; Hydrochloride: F.P.: 111–116° C.; Bromomethylate: F.P.: 161–165° C.
16.....	β -Diethylaminoethyl [α -nortricyclyl-(3)-m-trifluoromethyl benzyl] ether.	Base: B.P. _{0.2 mm.} : 114–118° C.; Hydrochloride: F.P.: 102–105° C.; Bromomethylate: F.P.: 160–162° C.
17.....	β -Diethylaminoethyl [α -methyl- α -nortricyclyl-(3)-p-fluorobenzyl] ether.	Base: B.P. _{0.1 mm.} : 126–132° C.; Hydrochloride: F.P.: 117–119° C.; Bromomethylate: F.P.: 174–178° C.
18.....	β -Diethylaminoethyl [α -methyl- α -nortricyclyl-(3)-p-bromobenzyl] ether.	Base: B.P. _{0.005 mm.} : 134–137° C.; Hydrochloride: F.P.: 147–150° C.; Bromomethylate: F.P.: 189–193° C.
19.....	β -Diethylaminoethyl [α -ethyl- α -nortricyclyl-(3)-benzyl] ether.	Base: B.P. _{0.1 mm.} : 130–133° C.; Hydrochloride: F.P.: 130–132° C.; Bromomethylate: F.P.: 125–129° C.

Example	Chemical nomenclature	Properties
20.	β -Diethylaminoethyl[α -(2-methyl-propyl)- α -nortriacyclic-(3)-benzyl] ether.	Base: B.P. _{0.03} mm.: 128-135° C.; Hydrochloride: F.P.: 107-109° C.; Bromomethylate: F.P.: 132-135° C.
21.	γ -Diethylaminopropyl[α -nortriacyclic-(3)-benzyl] ether.	Base: B.P. _{0.12} mm.: 125-132° C.; Bromomethylate: F.P.: 111-117° C.
22.	β -Pyrrolidinoethyl[α -nortriacyclic-(3)-benzyl] ether.	Base: B.P. _{0.065} mm.: 154-150° C.; Hydrochloride: F.P.: 123-126° C.; Bromomethylate: F.P.: 144-146° C.
23.	β -Morpholinylethyl[α -nortriacyclic-(3)-benzyl] ether.	Base: B.P. _{0.01} mm.: 135-145° C.; Hydrochloride: F.P.: 173-175° C.; Bromomethylate: F.P.: 72-73° C.
24.	β -Diethylaminoethyl[α -nortriacyclic-(3)-o-methyl benzyl] ether.	Base: B.P. _{0.06} mm.: 116-119° C.; Hydrochloride: F.P.: 110-114° C.; Bromomethylate: F.P.: 175-167° C.
25.	β -[N-methyl-pyrrolidyl-(2)] ethyl[α -nortriacyclic-(3)-p-chlorobenzyl] ether.	Base: B.P. _{0.01} mm.: 140-145° C.; Hydrochloride: F.P.: 143-147° C.

EXAMPLE 26:

Coated tablets containing 10 mg. of active principle.

a. Compound according to Example 1	10.0 mg.
granular corn starch	23.0 mg.
Aerosil	1.0 mg.
anhydrous secondary calcium phosphate	20.0 mg.
talc (free of iron)	2.5 mg.
magnesium stearate	1.0 mg.
lactose D 10	32.5 mg.
Compound according to Example 5	Total: 90.0 mg.
granular corn starch	10.0 mg.
Aerosil	23.0 mg.
anhydrous secondary calcium phosphate	1.0 mg.
talc (free of iron)	20.0 mg.
magnesium stearate	2.5 mg.
lactose D 10	1.0 mg.
	Total: 90.0 mg.

The above components are passed through a stainless steel sieve having a mesh width of 1 mm. and are mixed thoroughly for 30 minutes. The resulting product is pressed without previous granulation to kernels weighing 90 mg. and having diameter of 6 mm. and a radius of dishing of 5 mm.

These kernels then are coated in usual manners until a final weight of 165 mg. each.

EXAMPLE 27

Injection solution containing 10 mg. of active principle per 2 ml. of solution.

a. Compound according to Example 1 sodium dihydrogen phosphate monohydrate	10.000 mg.
disodium hydrogen phosphate dihydrate	6.254 mg.
bidistilled water, filled up to	3.8 mg.
b. Compound according to Example 5 bidistilled water, filled up to	1.00 ml. 10.0 mg. 2.00 ml.

The compounds are dissolved in the bidistilled water useful for injection purpose without warming, passed through a sterile Seitz-EKS-filter under aseptic conditions and in a nitrogen atmosphere and are filled in white 1 or, respectively, 2 ml. ampoules.

EXAMPLE 28:

Suppositories:

a. Compound according to Example 1
Witepsol H19 20 mg.
b. Compound according to Example 5
Witepsol H 19 1980 mg.
20 mg.
1980 mg.

The active compounds sieved to a grain-size of 100 μ are suspended homogeneously in the molten Witapsol and are poured to suppositories weighing 2.0 g. each at a temperature not exceeding 42°C.

5 The compounds and preparations herein above described are particularly useful as spasmolyties and, as long as the active compounds are tertiary amines, as antiallergics, antidepressives, and tremor inhibitors.

10 The treatment of spasm is effected by administering to persons suffering therefrom a pharmaceutical preparation of a compound of the general formula I, in particular a quaternary ammonium salt thereof and in particular orally in a dose of about 5 to about 20 mg. with persons suffering from the other symptoms (allergy, depression, tremors) the dose ranges from about 20 to about 50 mg. one to three times a day both for parenteral and oral administration, i.e., the total daily dose ranges from 20 to 150 mg. The treatment is continued until the symptoms have disappeared.

15

20

In a test, a tablet containing 10 mg. of compound G of Table 2 has been administered orally to a person suffering from spasms of the intestines. About 20 minutes after the administration the pains caused by the spasms disappeared. The same amount of the same compound has been administered to a person suffering from a dyskinesia of the bile-duct. The pains caused by the spasms disappeared 20 minutes after the administration of the tablet. Still another patient suffering from spasms of the intestinal tract after ileo-colectomia obtained a dragee according to Example 26 b containing the compound G of Table 2; the spastic pains disappeared with 30 minutes; no undesirable side effects have been observed.

What we claim is:

1. A basic α -nortricyclyl-(3)-benzyl ether having the general formula I

wherein R₁ is a member selected from the group consisting of hydrogen, the halogen atoms, the lower alkyl groups having from one to four carbon atoms, the trifluoromethyl group and the lower alkoxy groups having from one to four carbon atoms, R₂ is a member selected from the group consisting of the straight chain and branched chain alkyl groups having from one to four carbon atoms and the ethinyl group, —alk— is a member selected from the group consisting of

and A is a member selected from the group consisting of the groupment.

wherein R_3 and R_4 represent members selected from the group consisting of the lower alkyl groups having

from one to four carbon atoms and R₆ is a member selected from the group consisting of hydrogen the methyl and the ethyl group and the acid addition salts thereof.

2. A compound according to claim 1 wherein R₁ is 5 hydrogen, R₂ is a member selected from the group con-

sisting of hydrogen and the methyl group, —alk— is the methylene group and A is the diethylaminomethylene group, and the acid addition salts thereof with pharmacologically acceptable acids.

3. β -Diethylamino-ethyl-[α -nortricyclyl-(3)-benzyl] ether hydrochloride.

* * * * *
